(57) **CLAIM**

The new ornamental design for a hasp type closure assembly, as shown and described.

DESCRIPTION

FIG. 1 is a perspective view of a hasp type closure assembly according to a first preferred embodiment of my new design; FIG. 2 is a second perspective view of the hasp type closure assembly of FIG. 1;

FIG. 3 is a front elevational view of the hasp type closure assembly of FIG. 1;

FIG. 4 is a top plan view of the hasp type closure assembly of FIG. 1;

FIG. 5 is a bottom plan view of the hasp type closure assembly of FIG. 1;

FIG. 6 is a left side elevational view of the hasp type closure assembly of FIG. 1;

FIG. 7 is a right side elevational view of the hasp type closure assembly of FIG. 1;

FIG. 8 is a rear elevational view of the hasp type closure assembly of FIG. 1;

FIG. 9 is a perspective view of a hasp type closure assembly according to a second preferred embodiment of my new design;

FIG. 10 is a second perspective view of the hasp type closure assembly of FIG. 9;

FIG. 11 is a front elevational view of the hasp type closure assembly of FIG. 9;

FIG. 12 is a top plan view of the hasp type closure assembly of FIG. 9;

FIG. 13 is a bottom plan view of the hasp type closure assembly of FIG. 9;

FIG. 14 is a left side elevational view of the hasp type closure assembly of FIG. 9;

FIG. 15 is a right side elevational view of the hasp type closure assembly of FIG. 9; and,

FIG. 16 is a rear elevational view of the hasp type closure assembly of FIG. 9.

The dashed lines in FIGS. 1-16 represent environment and are for illustrative purposes only and do not constitute part of the claimed design. The phantom lines in FIGS. 8 and 16 define the border between claimed and unclaimed matter.
